In Germany April 22, 1937

3 Claims. (Cl. 242—78)

This invention relates to a method of and means for use in the heat treatment of metal bands.

Metal bands, particularly such as have been produced by rolling, are heat-treated generally by rolling them up and annealing the rolled up bands in an annealing furnace or a salt bath. In such treatment it has been found that the inner convolutions of the tightly wound band become heated much more slowly than the outer convolutions, and also that, when the annealing treatment is followed by quenching, the action of such quenching on the inner portions of the rolled up band is adversely affected, or frequently even entirely suppressed, by the slow conduction of heat. This slow conduction of heat is due not only to the long path the heat has to travel, which may amount to 80 mm. and more, depending on the thickness of the reel, but also to the fact that, even in the case of a tightly wound band, the very thin layer of stagnant air always present between the individual convolutions, acts as a heat-insulator.

A further drawback in the method hitherto employed is that, when the annealed reel is quenched in water or oil, it is impossible to avoid the formation of spots on the interior portions of the rolled up band, due to the uneven penetration of the quenching medium into the interstices between the individual convolutions of the reel. This formation of spots is, moreover, substantially intensified by the formation of steam, the corrosive action of the locally highly superheated steam on the metal frequently becoming unpleasantly noticeable.

The present invention aims at providing a method and a device which enable the foregoing drawbacks to be avoided.

To this end, according to the invention, the metal band to be subjected to heat treatment is wound up into a reel with the interposition of two narrow marginal strips of appreciable thickness and of such a form as to permit the flow of gas and/or liquid into the gaps between the individual convolutions of the roll, e. g. in the form of narrow strips of corrugated sheet metal. In this form the rolled up band is subjected to the annealing treatment and, on occasion, also to the subsequent quenching. The corrugated strips enable all parts of the band to be exposed uniformly to the action of heat in the annealing furnace or annealing salt bath, and during the subsequent quenching of the band reel also permit uniform access of the cooling medium to all parts of the band. In this

manner the inconveniences hitherto arising due to the slow conduction of heat and the uneven access of the cooling medium are obviated.

The strips of corrugated sheet metal are preferably inserted when winding the band, and are advantageously of such dimensions and so disposed that they cover only the narrow marginal portions of the band which are anyhow cut off and discarded as waste in the subsequent trimming of the band.

In order to enable the invention to be more readily understood, reference is made to the accompanying drawing which illustrates diagrammatically and by way of example one embodiment of apparatus suitable for carrying the invention into practical effect and in which

Fig. 1 is an elevation;

Fig. 2 is a cross section along the line A—B of Fig. 1; and

Fig. 3 is a cross section along the line C—D of Fig. 1.

The metal band A, coming from the reel of the band rolling machine (not shown in the drawing), first passes over a guide roller B and a brake C into a guide D, and from there on to a winding drum E. Between the guide D and the drum E is located a device F for correctly feeding and positioning the corrugated strips H from two drums G. As can be seen from Fig. 3, the device F consists of a shaft a, on which are slidably mounted two guide brackets b, which can be adjusted by means of set screws in accordance with the width of the band. The guide brackets each carry a guide c for the corrugated strips H winding off from the drums G and also a vertically disposed guide roller d guided by the edge of the band A, and a horizontally disposed guide roller e rolling on the band A.

A specially designed drum E, as shown in Fig. 2, is preferably used for winding the band A together with the corrugated strips H. The drum has a slit running along one side line, and in said slit is disposed a shaft g eccentrically mounted at f. h are two supporting rings which are pushed on to the drum E before the band is wound and are clamped in position by the eccentric shaft g at a distance from one another corresponding to the width of the band. After the winding has been completed, the clamping pressure is released and the wound up reel, together with the rings h, is removed from the drum E and introduced into the annealing furnace. The rings h then prevent the wound up reel from collapsing or otherwise altering its

shape under the action of the high temperature prevailing in the annealing furnace.

I claim:

- 5 1. An apparatus of the kind described, comprising rotatable means for winding a metal band thereon into a reel, means for controlling the advance of the metal band to said winding up means, a guide frame comprising two brackets in adjustably spaced relation to each other, an eye in 10 each of said brackets facing said winding up means, horizontal rollers on each of said brackets adapted to suspend said frame from said metal band when moving while allowing said frame to retain a stationary position in relation to said 15 winding up means, and vertical rollers on each of said brackets, laterally coacting with the edges of said band so as to maintain said frame in a fixed position relatively to the cross section of said moving band, at least two means for holding 20 a stock of metal strips and delivering the same therefrom through the eyes in said brackets respectively, to said winding up means, said holding means and also said guide frame being so disposed and arranged in relation to each other 25 and to said winding up means as to enable said strips to become continuously interposed between the convolutions of the band forming said reel and at a predetermined distance from the edges of said band.
- 30 2. An apparatus of the kind described, comprising a drum for winding a metal band thereon and into a reel, a pair of ring members for supporting said reel arranged on the drum in proximity to the edges of the band to be wound, a 35 slit in said drum along a side-line thereof, a shaft disposed in and along said slit and eccentrically

mounted in said drum so as to be adapted to be caused alternatively to protrude from and to be retracted into said drum, said shaft firmly holding said rings in position on said drum when it protrudes from the drum, means for controlling the advance of the metal band and further at least two means for holding a stock of metal strips and delivering the same therefrom in parallel and in spaced relation to each other, to said winding up means, said holding means being so disposed and arranged in relation to each other and to said winding up means as to enable said strips to become continuously interposed between the convolutions of the band forming said reel and at a predetermined distance from the edges 15 of said band.

3. An apparatus of the kind described, comprising rotatable means for winding a metal band thereon and into a reel, means for controlling the advance of the metal band, and further at least two means for holding a stock of metal strips and delivering the same therefrom in parallel and in spaced relation to each other, to said winding up means, and a guide frame having a pair of lateral extensions guiding the metal 25 strips, in parallel and in spaced relation to each other, to said winding up means, said guide frame being suspended from said moving metal band, and said holding means and said guide frame being so disposed and arranged in relation to each 30 other and to said winding up means as to enable said strips to become continuously interposed between the convolutions of the band forming said reel and at a predetermined distance from the edges of said band.

ERNST WEISSE.
